UNITED STATES PATENT OFFICE.

MARK A. ROSS, OF CHICAGO, ILLINOIS.

HEADLIGHT-CASING.

No. 882,924.

Specification of Letters Patent.

Patented Oct. 9, 1906.

Application filed April 17, 1905. Serial No. 313,133.

To all whom it may concern:

Be it known that I, MARK A. Ross, a citizen of the United States, residing at Chicago, in the county of Cook and State of Illinois, have invented a new and useful Improvement 5 in Headlight-Casings, of which the following is a specification.

My invention relates to improvements in the construction of locomotive-headlight 10 casings with a view to facilitating the insertion and retention of the transparent disks or plates.

In practice frequent breakage of the glass disks or plates occurs, and as the casings 15 have been hitherto usually constructed it has been necessary in replacing a disk to open the casing, pass the disk into it, and then fasten it from the inside against its seat in the forward part of the casing-front. 20 This manner of replacing a disk has been slow and troublesome, and my object is not only to make the operation of inserting a disk more easy than hitherto, but to provide a construction of disk-retaining means which 25 will hold the disk with great security and in a manner to lessen danger of breakage from jar in the travel of the locomotive.

Referring to the accompanying drawings, Figure 1 is a partly-broken view in side elevation of a locomotive-headlight casing in position on a locomotive and embodying the preferred form of my invention; and Fig. 2 an enlarged broken view in vertical section, taken through the frusto-conical front of the headlight, showing a modification of the 30 means for holding the disk in place.

Referring to Fig. 1, 4 is a locomotive-headlight casing secured in position on a locomotive-boiler jacket. 5. The casing is provided 35 on its front face with a hollow frusto-conical front or extension 6. The outer end of the projection 6 is open, and its outer edge is expanded, as shown, to form an annular curved socket 7, providing an inwardly-projecting 40 flange. Secured by rivets 8 to the inner surface of the extension and back of its socket 7 is an annular outwardly-opening seat 9, in which is confined a cushioning-ring 10, preferably of rubber, against which the transparent disk 11 is adapted to be seated through the open end of the extension. The disk is 45 releasably retained against the ring 10 by means of a split wedge-ring 12, preferably of 50 spring metal and half-round in cross-section, the flat side of which bears against the outer edge portion of the disk and the curved sur-

face against the edge of the socket portion 7, thereby clamping the disk between the rings 10 and 12.

In the modification shown in Fig. 2 the extension 6 has a collar 13 riveted to it; the collar having its outer edge beaded to form an annular curved surface 14 for engagement with the curved surface of the split ring 12. The outer end of the extension is contracted 65 and its outer edge beaded and provided with a rubber covering 15, forming a cushioning-seat for the disk. In the construction shown in Figs. 1 and 2 the split ring acts as an annular wedge which in expanding clamps the 70 disk against its seat with great security.

When a disk breaks, the ring 12, Figs. 1 and 2, may be contracted and withdrawn and the glass removed and a new disk be inserted, as described. Thus in the various constructions herein shown and described a disk 75 when it breaks may be readily removed and a new one inserted to seat it rigidly in position through the open end of the extension, thereby rendering the operation a simple and 80 expeditious one.

While I have shown my improvements applied to a headlight-casing for holding the front plate of glass, they may also be employed for holding the side plates of glass 85 usually provided in headlights and displaying the locomotive's number.

What I claim as new, and desire to secure by Letters Patent, is—

1. In a headlight-casing, the combination 90 with a casing-face having an opening for the insertion of a transparent plate, of a seat in said opening for the rear edge portion of the plate, an inwardly-projecting flange near the outer end of the casing-front, and an expandable and contractible wedge-ring adapted to be inserted through said casing-opening and extend between the plate and flange to engage said flange and clamp the plate against 95 said seat.

2. In a headlight-casing, the combination 100 with a casing-face having an opening for the insertion of a transparent plate, of a resilient seat in said opening for the rear edge portion of the plate, an inwardly-projecting flange 105 near the outer end of the casing-front, and an expandable and contractible wedge-ring adapted to engage said flange to clamp the plate against said seat.

3. In a headlight-casing, the combination 110 of a projecting face having an opening for the insertion of a transparent plate, and termi-

nating at its outer end in a curved annular socket, a curved annular seat in said opening, a cushioning-ring in said seat against which the plate is adapted to bear at its rear 5 edge portion, and an expansible and contractible split wedge-ring with a curved surface at which it is adapted to engage the in-

ner surface of the socket to clamp the plate against said seat.

MARK A. ROSS.
